UNITED STATES PATENT OFFICE

2,092,011

SPUD

Harry A. Musham, Chicago, Ill.

Application March 16, 1936, Serial No. 69,140

10 Claims. (Cl. 37—73)

(Granted under the act of March 3, 1883, as amended April 30, 1928; 370 O. G. 757)

This invention described herein may be manufactured and used by or for the Government for governmental purposes, without the payment to me of any royalty thereon.

5 This invention pertains to improvements in spuds for floating barges or other craft, where it is required to anchor the same in shallow water.

The principal object of the invention is to provide a spud which when not in use will extend 10 only slightly above the craft and thus avoid the necessity for opening low clearance bridges.

Another object of the invention is to increase the operative length of the spud without sacrificing clearance above the deck.

15 With these and other objects in view this invention consists in certain novel details of construction, combination and arrangement of parts to be more particularly hereinafter described and claimed.

20 Referring to the accompanying drawings in which corresponding parts are indicated by similar reference characters:

Fig. 1 shows a hull broken away centrally to display a spud well containing a telescopic spud 25 in retracted position;

Fig. 2 is a similar view to Figure 1 showing the telescopic spud with the interior main section thereof raised above the deck;

Fig. 3 is a similar view to Figs. 1 and 2 showing 30 both the main and extension telescopic sections of the spud lowered to a position where the exterior section engages the bottom of the stream;

Fig. 4 shows a section of a hull broken away 35 to display a spud well containing a modified form of telescopic spud;

Fig. 5 shows a hull broken away centrally to display a spud well containing another modified form of spud in which the sections are hingeably 40 united;

Fig. 6 is a plan view of the latching mechanism, shown in Figs. 1, 2, and 3, utilized for holding the exterior telescopic section in elevated position, and

45 Fig. 7 is a cross-section taken along the line 7—7 of Fig. 4, showing the interior of the telescopic sections.

Heretofore spuds were usually constructed in one solid or hollow post throughout their entire 50 length and consequently extended for some distance above the structure of the craft when not in use, thus preventing the craft from passing under bridges of low clearance, and it was primarily to avoid this cumbersome and inconvenient construction that the spud which forms

the subject matter of this invention was designed.

Referring to Figs. 1, 2, and 3, the numeral (1) indicates the hull of a dredge or similar type of watercraft, (2) the cabin or deck house and (3) a spud well, which may be flanged at its upper and lower extremities for attachment to the hull. Within the spud well (3) a telescopic type of spud (4) is slidably mounted. The spud (4) is made up of a main and an extension telescopic section, indicated respectively by the numerals (5) and (6), the former section being slidably mounted within the latter. The inner or main section (5) is provided at its lower extremity with a disc (7) which fits slidably within the extension section (6), and section (6) is provided at its upper extremity with an internal annular rim (8), in which the interior section (5) is slidably fitted. The disc (7) and the internal annular rim (8) are provided to prevent separation of the sections (5) and (6) when the spud is extended to full length, however other forms of construction may be used to accomplish this purpose without departing from the scope and spirit of the invention.

Adjacent the upper extremity of the spud well (3) is mounted a hoisting engine (9) on the drive shaft (10) of which is keyed a pinion (11) which meshes with a rack (12) formed along the exterior circumference of the main or interior telescopic section (5). This engine (9) is adapted to raise and lower the spud as desired. The upper extremity of the interior telescopic section (5) is drilled for the reception of a pin (13) which is longer than the interior diameter of the spud well and is provided to insure the inner section from being accidentally dropped through the well when it is brought to its lowest operating position.

The upper portion of the spud well is provided with a collar (14) on which is mounted an eccentric latching device (15) utilized to hold the extension section (6) in elevated position within the well when not in use. This latching device, shown in plan view in Fig. 6, comprises a circular disc (40) provided with a radially extending handle (41), the disc being rotatably mounted on a pin (42) projecting from the collar (14). The rotatable mounting is eccentrically located with respect to the circumference of the disc to provide surfaces on the periphery of the disc, of gradual increasing radius, to contact the external surface of the extension section (6) of the telescopic spud, as the handle (41) is rotated in a clockwise direction, and thus produce a wedging action,

which when applied at any location along the extent of the spud section (6), will lock the section (6) to prevent longitudinal movement thereof.

When it is desired to put the spud into operation the hoisting engine or winch (9) having the driving pinion (11) which meshes with the rack (12) as described above, moves the inner telescopic or main section (5) upward to its full extent, in which position the inner disk (7) contacts the collar (8). To lower the spud into operative position the latching mechanism (15) is first released, the engine is then reversed, and the spud lowered until its lower end embeds itself in the bottom of the stream, in which position it holds the craft in place. When it is desired to release the craft the hoisting engine raises the inner or main section (5) of the spud to its highest position. The extension section (6) is then locked in elevated position by the latching device (15), and the inner main section is lowered into the outer or extension section.

A modified form of telescopic spud is shown in Fig. 4. In this type of spud the main section (5') is raised and lowered by means of a pinion (11) and the extension section (6') by a screw (16). The pinion (11) which raises and lowers the main section (5') by engagement with the rack (12) is keyed to the driven shaft of a hoisting engine (9), as described above, but which is not shown in this figure.

In this type of spud the inner or extension section (6') is moved longitudinally along the central axis of the main section (5') by means of a screw (16) which is rotatably mounted centrally within the body of the spud. The upper extremity of the main section is fitted with a bearing member (17) through which the upper unthreaded portion (18) of the screw (16) projects. This unthreaded portion of the screw is held within said bearing by the annular collars (18) and (18') which prevent longitudinal movement of the screw. The portion (20) of the screw which projects above the upper collar (18') is squared so as to be readily turned by means of a wrench or hand wheel or a gear which may be connected to an electric motor. The inner extension section (6') at its upper extremity is fitted with an internally threaded circular bearing member (21) which fits the threads of the screw (16) and a similar internally threaded circular member (22) is rigidly fitted to the interior of the extension section (6') at about midway its length. Below the internally threaded member (22) the screw is provided with a collar (31) to prevent accidental separation of the main and extension sections (5') and (6'). The extension section (6') is provided with laterally projecting guide pieces (23) and (24) which move in the slotted path provided between the semicircular members (25) and (26), fitted within the interior of the main section (5'). By this construction the extension section can only have longitudinal movement, and thus the rotation of the screw which is fitted in the bearing members (21) and (22), causes this section to move longitudinally in either direction depending on the direction of rotation of the screw.

Thus in the operation of the device, the turning of the screw by a wrench or hand wheel or a small electric motor, mounted on the top of the main section (5'), lowers and raises the extension section (6') while the main section of the spud which is fitted with a rack (12) is hoisted or lowered by the engine (9) in the same manner as the spud described in Figs. 1, 2, and 3. When using the

spud the main section is lowered to its full length, and then if further length of spud is required the screw (16) is revolved by any of the means stated above and the extension section is lowered until its lower end embeds itself in the bottom of the stream. To release the craft the main section is hoisted by the hoisting engine and then the extension section is elevated by operation of the screw (16).

Another modification of the improved spud is shown in Fig. 5. This type of spud may be made with two or more sections united by hinged joints (29). The sections are provided with racks so that they can be readily raised and lowered by a hoisting engine which rotates a driving pinion in mesh with said racks, as were the main sections of the spuds described above.

The spud illustrated in Fig. 5 is provided with two sections (27) and (28) which are projected downwardly through the spud well (3) and elevated therethrough by means of the engine (9), which rotates the pinion (9) engaging the racks (12).

As the upper section (27) of the spud is elevated through the well (3) and is then reclined across the roof of the deck house, it is necessary that the spud bend in the locality of upper front end of the deck house; so in order to prevent damage to the deck house and to relieve friction between the same and the spud, rollers (30) are provided as shown in Fig. 5.

To put the spud into operation it is necessary to raise the upper section to a vertical position by hydraulic hoists (not shown) similar to those used on motor trucks. The two sections are then projected through the spud well until the lower section is sufficiently embedded in the bottom of the stream to anchor the craft. In raising the spud it is necessary to use the hydraulic hoists to lower the upper section onto the roof of the deck house.

It will be apparent that the above described mechanisms may be altered and the arrangement changed in various ways. The telescopic cylinders composing the spud sections may be of the hydraulic type, in which case the hoisting engine would be substituted by an engine driven pump. Other similar modifications are possible but such modifications do not constitute a departure from the scope and spirit of the invention.

Having described my invention, what I claim as new and wish to secure by Letters Patent is:

1. An anchoring device for watercraft comprising a spud well and an extensible spud composed of a multiplicity of foldable sections adapted for slidable movement through said well, operating means, and means in connection with said spud adapted to engage said operating means to move the spud through said spud well.

2. An anchoring device for watercraft comprising a spud well and an extensible spud composed of a multiplicity of telescopically associated sections adapted for slidable movement through said well, operating means including a rotatable pinion, and means in connection with said spud comprising a longitudinally extending rack adapted to engage said pinion to move the spud through said spud well.

3. An anchoring device for watercraft comprising a spud well and an extensible spud composed of a multiplicity of hingeably united foldable sections adapted for slidable movement through said well, operating means, and means in connection with said spud adapted to engage

5 said operating means to move the spud through said spud well.

4. An anchoring device for watercraft comprising a spud well and an extensible spud composed of a multiplicity of hingeably connected foldable sections adapted for slidable movement through said well, operating means, and means in connection with each of said sections adapted to engage said operating means to move the spud through said spud well.

10 5. An anchoring device for watercraft comprising a spud well and an extensible spud composed of a multiplicity of foldable sections adapted for slidable movement through said well, operating means, and means comprising a rack in connection with said spud adapted to engage said operating means to move the spud through said spud well.

15 6. An anchoring device for watercraft comprising a vertical spud well and an extensible spud composed of a multiplicity of telescopically associated sections adapted for slidable movement through said well, means for locking the outermost telescopic section and means in connection with said spud adapted to engage said operating means to move the spud through said spud well.

20 7. An anchoring device for watercraft comprising a spud well and an extensible spud composed of a multiplicity of telescopically associated sections adapted for slidable movement through said well, means for locking the outermost telescopic section, operating means, and means in connection with said innermost telescopic sec-

25 tion adapted to engage said operating means to move the spud through said spud well.

8. An anchoring device for watercraft comprising a spud well and an extensible spud composed of a multiplicity of telescopically associated sections adapted for slidable movement through said well, operating means, and means in connection with said outer telescopic section adapted to engage said operating means to move the spud through said spud well, and additional 10 means adapted to move the inner telescopic section within said outer telescopic section.

15 9. An anchoring device for watercraft comprising a spud well and an extensible spud composed of a multiplicity of telescopically associated sections adapted for slidable movement through said well, operating means, and means in connection with said outer telescopic section adapted to engage said operating means to move the spud through said spud well, and additional 20 means comprising a screw adapted to move the inner telescopic section within said outer telescopic section.

25 10. An anchoring device for watercraft comprising a spud well, a spud operatively mounted in the well with its lower end normally disposed approximately flush with the lower end of the well, said spud being formed of collapsible sections, and means in connection with said sections for projecting the lower end of the spud a 30 predetermined distance below the well, said means including a rack and pinion, the rack being mounted on the spud.

HARRY A. MUSHAM.
